UNITED STATES PATENT OFFICE.

DAVID E. WOLFF, OF WELSH RUN, PENNSYLVANIA.

DESIGN FOR THILL-COUPING.

Specification forming part of Design No. 5,306, dated October 3, 1871.

To all whom it may concern:

Be it known that I, DAVID E. WOLFF, of Welsh Run, in the county of Franklin and State of Pennsylvania, have invented an Improved Design for Thill-Coupling; and I do hereby declare the following to be a full, clear, and exact description of the same, reference being had to the accompanying drawing forming part of this specification, in which—

Figure 1 is a perspective view, and Fig. 2 a top view, the barrel being shown in section.

Similar letters of reference in the accompanying drawing denote the same parts.

This invention relates to that class of thill-couplings in which the thill-iron is secured to the clip by means of a spring-bolt; and it consists of a new and improved design for such couplings, the principal feature of which consists in forming the bolt with an elongated stem terminated by a knob or thumb-piece, and in arranging the spiral spring around the stem and incasing both stem and spring in a closed tube or barrel projecting from the side of the clip in line with the holes that form the bearings of the bolt.

In the drawing, A is the axle; C, the clip; B, the bolt; b, the stem of the bolt; s, the spiral

spring surrounding the stem; k, the knob on the end of the stem; and D, the closed barrel incasing the stem and spring, the several parts all being constructed and arranged with relation to each other, substantially as shown in the drawing.

One great advantage of this construction and arrangement is that it excludes all dirt, snow, ice, &c., from the apparatus, thus keeping the latter not only in a better condition with respect to neatness and beauty, but also preventing the parts from getting out of working order by reason of the causes referred to. Other incidental advantages are cheapness of construction, durability, and convenience of operation, all of which result from the employment of the closed tube and its arrangement to incase the other parts, in the manner shown.

Having thus described my invention, what I claim as new is—

The design for thill-couplings, substantially as herein described and shown.

DAVID E. WOLFF.
